UNITED STATES PATENT OFFICE.

PAUL W. SEEWER, OF GENEVA, SWITZERLAND.

DEVICE FOR GOVERNING WATER-WHEELS.

1,282,470.

Specification of Letters Patent.

Patented Oct. 22, 1918.

Application filed August 30, 1916. Serial No. 117,686.

To all whom it may concern:

Be it known that I, PAUL W. SEEWER, a citizen of the Swiss Confederation, and a resident of the city of Geneva, Switzerland, have invented a new and Improved Device for Governing Water-Wheels, of which the following is a full, clear, and exact description.

The present invention relates to a governing device for tangential water wheels, pelton wheels and so on.

The main object of the invention is to control the working of the water wheel by varying the shape of the water jet issuing from the nozzle.

I attain this object by arranging within the nozzle movably arranged guide-plates which may be moved into or within the water current in the nozzle in such a manner that either a solid jet leaves the nozzle or a jet which is totally split up in such a way that the issuing water cannot act on the wheel.

In a preferred form of construction I arrange a centrifugal governor which controls the guide-plates, said governor being connected with the plates by a suitable transmission gear, fluid relays and so on, which governor moreover controls the axial movement of a needle arranged in the nozzle, the axial displacement of which being used for varying the size of the jet issuing from the nozzle. The action of the guide plates may be suitably combined with that of the needle, so that in case of emergency the guide plates are rapidly turned across the water current in such a manner that the nozzle delivers a jet wholly split up and unable to impinge upon the vanes. The water wheel may be prevented from racing in a rapid manner and by simple means.

The present invention also comprises other features which will appear in the course of the subjoined description.

Reference is to be had to the accompanying drawings forming a part of this specification, and showing in a sectional elevation one mode of construction in a diagrammatical manner by way of an example.

In the drawing 1 designates a casing which is connected to a main. The casing 1 is provided with a nozzle 2 within which a needle 3 of well known construction is arranged. The needle 3 is movably arranged in a sleeve 4 fixed in the casing 1 concentrically to the nozzle 2. The front end of the

needle 3 is tapering and formed in the usual manner so that it may close the orifice of the nozzle 2. The hind end of the needle 3 is provided with an annular flange 5 working as a piston in a cylinder 6 attached to the casing 1. The shaft 7 of the needle is hollow and contains a rod 8 of a piston 9 which works in a second cylinder 10. Between the sleeve 4 and the casing 1 guide plates 11 are rotatably mounted. Each plate 11 is provided with a stud 12 projecting through a slot 13 of the hollow shaft 7 into a ring-groove or annular depression near the front end of the piston 9.

It will be noted that each of the studs 12 of the plates 11 is provided at its lower end with an outwardly extending rod 12', to the outer end of which a short stud 12'' is secured, which engages into a groove 8' formed in the end of rod 8, which engages the piston 9. It will thus be seen that when the piston 9 is moved in its axial direction, the plates 11 are turned around the axis of their studs in such a manner that the plates, which normally run parallel to the axis of the nozzle 2, form an angle therewith. The jet issuing from the nozzle is split up more or less according to the size of the angle inclosed by the plates 11 and the axis of the nozzle.

The cylinder 6 is connected to a distributing valve 14 by means of pipes 15, 16. Within a chamber of the valve body a piston 17 is slidably mounted which is linked to a rod 18. The rod 18 is connected at one end with the sleeve of a centrifugal governor 20 and at the other end to a rod 21 linked to a bell crank lever 22. The lever 22 is by means of a rod 23 linked to the piston 5.

The piston 17 which is provided with a channel 24 controls the orifices of the pipes 25, 26 and 27 and the outlet opening 28. The pipes 25, 26 lead from the casing 1 to the cylinder 6. A branch 29 of the pipe 26 leads to a second valve 30 having a piston 31. The latter controls the orifices of the pipes 27, 29 and 32 the latter of which leads from the valve 30 to the cylinder 10. The piston 31 is provided with a chamber 33 in which a piston 34 is slidably arranged. The piston 34 is fixed to a rod 35 linked to the rod 18. The chamber 33 is filled with oil and the piston 34 is provided with a bore 36 which may be partly or wholly closed by a screw 37.

The device works as follows:
In the normal position with full load on,

2
the needle 3 is withdrawn from the nozzle 2 and the guide plates stand parallel to the axis of the needle 3. If now the speed of the governor 20 increases by slowly decreasing load the piston 31 will not be moved at all as the oil in the chamber 33 has sufficient time to flow from one side of the piston 34 to the other through the opening 36. The pressure on both sides of the piston 9 does not change and the piston 9 and therewith the guide plates 11 remain stationary. The piston 17 however is raised to such position that the pipes 25, 26 on the one hand and the pipes 15, 28 on the other communicate respectively. The pressure in the part 38 of the cylinder 10 rises and the piston 5 is moved toward the nozzle 2, thus causing the needle 3 to throttle the discharge through said nozzle. The piston 5 presses the fluid out of the chamber 39 through the conduits 15, 24 to the outflow pipe 28. As soon as a piston 5 starts, the leverage 23, 22, 21, 18 is set in motion whereby the piston 17 is brought back to its initial position cutting off the communication between the pipes 15, 28 and 25, 26 respectively.

If by increasing load the governor 20 falls the piston 31 is again not moved at all and only the piston 17 is lowered. The pipe 25 is put in communication with pipe 15 and the part 38 of the cylinder 6 with the channel 24. The piston 5 and therewith the needle 3 moves backwardly and the nozzle is opened. The piston is brought back to its initial point by the mechanism 18 to 23 in the well known manner.

If the governor rises quickly, the oil in the chamber 33 may not pass from one side of the piston to the other and the rising piston 34 being coupled by the oil with the piston 31 takes the latter with it. At the same time the piston 17 is going upward. The pressure on the two sides of the piston 9 is now changed. The fluid from the part 40 of the cylinder 10 escapes through the conduits 16, 15, 24, 28 and pressure fluid enters into the cylinder part 41 through the conduits 25, 29 and 32. The piston 9 is rapidly moved and moves thereby the guide plates 11. The movement of the plates 11 causes the splitting up of the jet issuing from the nozzle 2 which jet is solid as long as the plates 11 are parallel to the axis of the needle 3. A deflecting of the plates 11 is sufficient to prevent the jet from doing any work. At the same time as the plates 11 are moved the needle 3 is steered as above described and closes the nozzle 2 by and by. The speed of its regulating action may be chosen according to requirements; to vary the regulating speed a valve 42 may be inserted in the pipe 26. During the operation of setting the plates 11 the oil in chamber 33 will flow

from one side of the piston 34 to the other, the piston 31 pressing downwardly owing to its weight. By the motion of piston 5 the pistons 17 and 34 are brought back to their original positions and upon return of piston 31 to its initial position the piston 9 is brought back setting the plates 11 parallel to the flow of the water through the nozzle 2. The energy required for the regulation is very small, the speed of regulation in emergency cases is very great, without causing a dangerous increase in the pressure of the mains, as the closing of the nozzle by means of the needle may be made as slow as desired. Although I have described one form of construction I wish it clearly understood that I do not confine my invention to the particular form of the device as shown and described. Various changes may be made without departing from the spirit of my invention.

What I claim and wish to secure by Letters Patent is:

1. In a governing device for water wheels having a nozzle, movable guide-plates adapted to be set parallel and across the axis of the nozzle, means for adjusting the orifice of the nozzle, means on said first named means for controlling its movement, a piston within said second means for controlling the movement of said guide plates, fluid relays controlling said second means and said piston, and means for controlling said fluid relays substantially as described.

2. In a governing device for water wheels having a nozzle, the movable guide plates adapted to be set parallel and across the axis of the nozzle, a needle adapted to adjust the orifice of the nozzle, a hollow piston on said needle controlling the movement thereof, a second piston arranged within the first named piston controlling the movement of the guide-plates, fluid relays controlling said pistons and a governor controlling said fluid relays substantially as described.

3. In a governing device for water wheels having a nozzle the deflecting plates adapted to be set parallel and across the axis of the nozzle, a needle adapted to adjust the orifice of the nozzle, a hollow piston on said needle and controlling the movements thereof, a second piston arranged within the first named piston and adapted to actuate said deflecting plates, fluid relays controlling said pistons, and a governor controlling said fluid relays substantially as described.

In testimony whereof I affix my signature in presence of two witnesses.
